Harry Odzer, New York, N. Y.

Application October 20, 1939, Serial No. 87,748

Term of patent 3½ years

To all whom it may concern:

Be it known that I, Harry Odzer, a citizen of the United States of America, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The de-

sign unit is contained between the dot and dash lines which unit is repeated in regular succession as indicated by the extensions beyond the unit boundaries.

My design comprises a series of warpwise stripes arranged in a whorl pattern on a contrastingly colored background as shown.

I claim:

The ornamental design for a textile fabric, substantially as shown and described.
